(57) **CLAIM**

The ornamental design for an elevation spreader as shown and described.

DESCRIPTION

FIG. 1 is a front-right-top perspective view of the elevation spreader showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view from another angle of view thereof;

FIG. 9 is a perspective view from another angle of view thereof, and

FIG. 10 is a perspective view thereof, showing the elevation spreader in an alternate configuration; and,

FIG. 11 is a perspective view thereof, showing the elevation spreader in a separated state.
